CLAIM

The ornamental design for an external housing and mounting bracket for forced-air scent dispersal device as shown and described.

DESCRIPTION

FIG. 1 is a perspective view of the top side, rear side, and left side, of an external housing and mounting bracket for a forced-air scent dispersal device showing the new design. FIG. 2 is a perspective view of the top side, rear side, and right side thereof;

FIG. 3 is a perspective view of the top side, front side, and left side thereof;

FIG. 4 is a perspective view of the top side, front side, and right side thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a rear side elevational view thereof; and,

FIG. 10 is a front side elevational view thereof.

The broken lines in the drawings illustrate environmental subject matter that forms no part of the claimed design.
